CLAIM

The ornamental arrangement of an absence of voltage display device, as shown and described.

DESCRIPTION

FIG. 1 is a front isometric view for a novel design of an absence of voltage display device;

FIG. 2 is a rear isometric view thereof;

FIG. 3 is a front view thereof;

FIG. 4 is a top view thereof;

FIG. 5 is a first side view thereof;

FIG. 6 is a second side view thereof;

FIG. 7 is a bottom view thereof; and,

FIG. 8 is a rear view thereof.
